UNITED STATES PATENT OFFICE.

IRVING EYER, OF WILMINGTON, DELAWARE

STAMPING-MACHINE.

No. 815,805.

Specification of Letters Patent.

Patented March 20, 1906.

Application filed July 29, 1905. Serial No. 271,881.

To all whom it may concern:

Be it known that I, IRVING EYER, a citizen of the United States, residing at Wilmington, in the county of Newcastle and State of Delaware, have invented certain new and useful improvements in Hand-Stampers; and I do hereby declare the following to be a full, clear, and exact description of the invention, such as will enable others skilled in the art to which it appertains to make and use the same.

This invention relates to certain improvements in hand-stamps.

An object of the invention is the production of an improved stamping-machine for performing the functions of a hand-stamp and which shall be durable in construction and capable of ready adjustment to bring various combinations of printing characters in line or to the printing position and which will avoid certain objections incidental to hand-stamps having the ordinary flexible bands carrying rubber type.

The invention consists in certain novel features in construction or in arrangements or combinations of parts, as more fully set forth hereinafter.

Referring to the accompanying drawings, which show for purposes of explanation a construction as an example of a device within the spirit and scope of my invention, Figure 1 is a side elevation having portions broken away to show various otherwise hidden parts. Fig. 2 is an end elevation. Fig. 3 is a vertical section. Fig. 4 is a plan view of the bottom or face plate of the main frame. Fig. 5 is a detail perspective of the universal locking-bar.

In the specific example illustrated the main frame of the stamp comprises the vertical parallel uprights 1 and the top cross-bar 2, having the central vertical guideway or tubular portion 3 usually elongated vertically.

4 is a horizontal face or bottom plate between the uprights 1 and secured to the bottom edges thereof. This face-plate is longitudinally slotted at 5 to permit the projection therethrough of the printing characters set to printing position, as hereinafter set forth.

50 The uprights 1 at their inner faces are formed with the parallel longitudinal grooves or slideways 6. The lower ends of these grooves are closed by the plate 4. A reciprocating yoke-frame is confined between the main-frame uprights to slide vertically within

the main frame. This yoke-frame comprises the top or cross plate 7, having the depending end plates or heads 8 arranged with their outer vertical faces in sliding engagement with the inner vertical faces of the uprights 1 and having outwardly-projecting rigid studs or pins 9 confined to move vertically in the guideways 6. At their inner faces these end heads 8 are formed or provided with the alined circular bosses or enlargements 10.

11 is a horizontal rigid metal tube or hollow cylinder arranged between said bosses with its end edges abutting against the vertical inner faces of said bosses. The bosses are usually of greater diameter than the cylinder, which is preferably arranged concentrically with the bosses, so that the bosses form stop-shoulders at the cylinder ends. The cylinder is secured usually by pins or machine-screws 12, passed through the yoke-frame ends and into the cylinder ends. The cylinder is formed with a longitudinal slot 13 throughout the length thereof and usually arranged at the top thereof, and the bosses 10 are vertically slotted or recessed at 14 at the ends of the slot 13 to receive and guide the ends of a universal locking-bar 15, which extends throughout the length of the tube 11, fitting loosely in the slot 13 thereof. The universal locking-bar is movable radially of the tube or cylinder and is yieldingly upheld by springs 16, tending to force the top edge of the bar above the plane of the top surface of the tube. The springs 16 are seated in sockets in the bosses below the recesses 14 and are usually in the form of expansive coiled springs receiving pins 17, rigid with and depending from the ends of the locking-bar 15. The locking-bar throughout its longitudinal outer or top edge is beveled off in opposite directions to form the outer locking or knife edge 18 for the purposes hereinafter set forth.

I mount the printing elements on the tube 11 and between the bosses 10 or yoke ends. The printing elements consist of a series of independent rotary parallel, preferably similar, disks 19, closely and loosely arranged on said tube and confined thereon between the shoulders formed by the bosses. Each disk is provided with a series of properly spaced or separated printing characters arranged around its periphery. The printing characters can be cut in the metal of the disk or can be separately formed and applied to the edge 110

of the disk. I preferably provide each disk with all the letters of the alphabet, together with such punctuation or other marks and spaces as may be deemed necessary. The printing characters of a disk are so spaced or arranged as to present but one character at a time at the printing position. I usually provide about twenty-eight of the preferably similar disks. Each disk is formed with a central opening of a size to snugly receive said tube and permit the disk to freely turn thereon when released from the locking-bar. The edge of the disk surrounding said central opening is formed with a series of V-shaped notches or depressions 20, in number equal to the number of depressions or spaces between the type-faces of the disk and preferably arranged in the radial planes of said spaces between the type-faces. The depressions 20 are formed to receive the tooth or locking edge of the locking-bar which enters a notch of each disk, and thus locks the entire row of disks against accidental displacement. The disks can be separately or independently rotated by hand to present any desired letter or printing-mark at the printing-point and by means of the series of disks to provide a row of any desired combination of letters at the printing-point. By reason of the opposite inclined surfaces of the notches 20 and the locking-bar edge the disks can be easily turned in either direction by the fingers against the pressure of the locking-bar, which slips in and out of and snaps from notch to notch. The slot in the bottom or face plate of the frame is of a width and length to expose only the row of letters located at the printing position, and hence said plate serves as a guide in locating the stamp to make the imprint at the desired point or portion of the sheet or article to be stamped, and also said face-plate can serve as a guide in adjusting each disk to bring the desired letter to the printing-point.

21 represents side plates secured to the yoke and closing the sides thereof above the row of printing-disks.

22 is a tubular vertical stem or handle rigid with top plate 7 of the yoke and projects loosely through the tubular portion 3 of the main frame and to a point above the same.

23 is a knob or handle secured on and closing the upper end of the tube 22.

24 is a coiled expansive spring arranged in the tube 22 and compressed between the knob 23 and a pin or rod 25, passed diametrically through and secured in the tubular portion 3 and loosely through the tube 22. The tube 22 is provided with longitudinal slots to receive said pin and permit reciprocation of the tube thereon. The front slot is provided at its ends with depressions or sockets 26 to receive the head 27 of the pin 25. The pin 25 passes loosely through the tubular portion

3 and at its rear end is threaded to receive the nut 28, by adjusting which the head 27 of the pin 25 can be drawn into either depression 26 to lock the yoke at either its depressed or elevation position.

I preferably provide an inking attachment, consisting of a pan or holder 29, for the ink-pad 30, having end arms 31 extending upwardly and outwardly therefrom at an inclination and at their upper ends pivotally joined by horizontal screws or pivot-pins to arms 32, rigid with and extending rearwardly from the main-frame uprights 1. The inking device is moved to and from inking position by the links 33 at their upper ends pivotally joined to the lower rear portions of the end heads of the yoke and at their lower ends pivotally joined to the arms 31 about midway the lengths of said arms. The end heads of the yoke are recessed at their outer faces (see 34) to receive said links 33 between said end heads and the inner faces of the uprights 1 and permit the swinging movement of said links from about their normal upright positions to a horizontal position, which they assume when the yoke is forced down to printing position. When the yoke is in its normal elevated position, in which position it is usually held by the spring 24, the inking device is in its normal position—that is, in inking position—with the trough 29 beneath and arranged longitudinally of the row of disks and with the inking-pad 30 drawn up against the row of type located at the printing position. The printing device is held in this position by the spring 24 and the yoke through the medium of the links 33.

To operate the hand-stamp to make an impression or imprint, it is merely necessary to press down the knob 23, which causes the reciprocation of the yoke against the tension of the spring 24, until the printing-type in the printing position have projected through the slot in the face-plate into engagement with the object being printed. This operation can be repeated as many times as desired without changing the location of or adjustment of the type. As the yoke starts on its downward movement the links 33 throw the inking device rearwardly from the disk and from the path of downward movement thereof.

The studs 9 are preferably arranged concentric with the tube 11, and said studs guide the yoke in its vertical reciprocation. The type-disks being preferably loosely assembled on the tube can be removed, if found necessary for any purpose, by removing the end screws 12, thereby releasing the tube, so that the same can be removed from the yoke with the disks thereon. The yoke itself can be removed from the frame, if found desirable for any purpose, by removing the face-plate from the frame, so that the studs 9 can slide out through the lower open ends of the

grooves 6 after the pin 25 has been removed from the handle-tube and the knob 23 has been taken off.

What I claim, and desire to secure by Letters Patent of the United States, is—

1. In a stamping-machine, in combination, a main frame having a tubular guide, a reciprocatory yoke provided with the printing elements and having a longitudinally-slotted tubular plunger or handle portion slidable through said guide, a coiled spring within said tubular plunger, and a removable pin forming an abutment for said spring, said pin passed removably through said guide and through the slots of said plunger and having opposite end heads, one of which is adjustable, whereby the pin can be tightened to lock the plunger against reciprocation through the guide. 75
2. In combination, a main frame having a tubular guide provided with diametrically opposite holes, a reciprocatory yoke provided with printing elements and having a tubular plunger or handle portion slidable through said guide, said plunger having diametrically opposite longitudinal slots registering with said holes, a coiled spring within said plunger, a removable pin passed diametrically through said plunger and extending into said holes and forming an abutment for said spring, said pin having an end head for locking engagement with said plunger. 80
3. In combination, a main frame having a tubular guide having diametrically opposite radial holes, a reciprocatory yoke provided with printing elements and having a tubular plunger or handle portion slidable through said guide and formed with diametrically opposite longitudinal slots registering with said holes, a coiled spring within said plunger, and a diametrically adjustable removable pin passed diametrically through said plunger and forming an abutment for said spring, said pin having a head at one end arranged in one of said holes, the opposite end of said pin being threaded and provided with an adjustable head located in the other hole, said plunger having depressions at opposite portions of one of said slots with which one of 85 said heads is adapted to have locking engagement. 90
4. In a stamping-machine, in combination, a main frame, a reciprocatory yoke having recessed end heads, a series of approximately similar type-disks carried by said yoke and arranged side by side between said heads and on one axis, each disk being independently turnable in either direction and having peripheral printing characters, and a universal spring-pressed locking-bar for and arranged within said disks and between and carried by said heads and provided with supporting-springs in said recesses, substantially as described. 95
5. In combination, a main frame, a reciprocatory yoke having end heads, a horizontal tube extending between and fixed to said heads and formed with a longitudinal slot, a series of type-disks confined and independently turnable on said tube and having depressions around their central openings, and a spring-pressed universal locking-bar between said end heads and arranged longitudinally of said tube and within said slot and normally in locking engagement with a depression of each type-disk. 100
6. In combination, a main frame, a yoke provided with a fixed barrel, a series of independently - rotatable type - disks loosely mounted on said barrel and having central openings receiving the same, each disk having a series of oppositely - beveled notches around its central opening and provided with printing characters around its periphery, and a spring-pressed universal locking-bar arranged longitudinally within said barrel and having a single oppositely-beveled locking edge in locking engagement with a notch of each disk. 105
7. In a stamping-machine, in combination, a yoke, a series of parallel type-disks having central openings and all mounted on the same axis and independently rotatable in either direction and having printing characters arranged on their peripheries, and a concealed spring-pressed universal locking-bar arranged longitudinally within said openings of the disks and constantly held pressed outwardly to and in locking engagement with all of said disks, substantially as described. 110
8. In a stamping-machine, in combination, a yoke, a series of parallel type - disks all mounted on the same axis and independently rotatable in either direction, each disk having a central opening and a series of notches around said opening, each notch having similarly-inclined walls, and a spring-pressed radially - movable universal locking - bar arranged longitudinally of said series of disks and within the same and having an oppositely beveled or inclined locking edge in locking engagement with a notch of each disk, whereby any disk can be turned in either direction, substantially as described. 115
9. In combination, a main frame, a reciprocatory yoke mounted therein, a fixed tube carried by said yoke, a series of independent disks loosely mounted and confined to turn on said tube, each disk having a central opening to receive said tube and having type representing the letters of the alphabet arranged around its periphery, and a universal spring-pressed locking-bar arranged longitudinally within said tube and series of disks and carried by said yoke independently of said tube and disks and yieldingly holding said disks against accidental turning and in set position, whereby the disks can be independently turned by the fingers in either direction. 120
10. In a stamping-machine, in combination, a main frame, a reciprocatory yoke 125

therein having end heads, a longitudinally-slotted tube between said end heads, means removably securing said tube to said end heads, a series of type-disks removably mounted on said tube and confined between said heads and having notches arranged around their central openings, and a universal locking-bar arranged within said tube and disks and between and supported by said end heads and provided with springs yieldingly holding the bar into engagement with the notched edges of the disks, said bar being removably arranged within the tube and disks.

11. In combination, a main frame, a reciprocatory yoke having end heads provided at their inner faces with bosses, a horizontal tube secured between and abutting against said bosses, a series of type-disks loosely mounted on said tube and between said bosses, and a spring device yieldingly holding said disks against accidental turning and in

set position, said device being supported by said end heads and independently of said tube and the disks, substantially as described.

12. In combination, a main frame, a reciprocatory yoke having end heads, a tube secured to and between said heads and having a longitudinal slot, said end heads having recesses at the ends of said slot, a series of type-disks mounted on said tube and having notches around their central openings, a universal locking-bar arranged in said slot and extending into said recesses and arranged to engage a notch of each disk, and springs yieldingly pressing said bar outwardly, substantially as described.

IRVING EYER.
